FIG. 7 -

FIGS. 1 and 3 are side and front elevations respectively, of a vertical take-off airplane showing our new design with the wings in take-off position;

FIGS. 2, 4 and 5 are side and front elevations and a top plan view, respectively, illustrating the vertical take-off airplane with the wings lowered to horizontal flight position;

FIG. 6 is a front perspective view thereof, taken from the top, with the wings lowered; and

FIG. 7 is a rear perspective view thereof, taken from the bottom, with the wings in raised position.

The dominant features of our design are shown in solid lines in the drawings.

We claim:

The ornamental design for a vertical take-off airplane, substantially as shown and described.
